UNITED STATES PATENT OFFICE.

MELVILLE D. JONES, OF BOSTON, MASSACHUSETTS.

DESIGN FOR HOOKS.

Specification forming part of Design No. 7,412, dated May 5, 1874; application filed March 13, 1874.
[Term of Patent 3½ years.]

To all whom it may concern:

Be it known that I, MELVILLE D. JONES, of Boston, Suffolk county, Massachusetts, have invented a Design for Hooks, of which the following is a specification:

The nature of my design is fully represented in the accompanying photographic illustration, to which reference is made.

The hook embraced in this design is of ordinary form in its exterior configuration. The body of the hook is composed of an annular surrounding bar or frame, *a*, the area included within this bar or frame being occupied by a series of vertical posts or columns, *b b*, of

a suitable figure, upon the outer face of each of which a star, *c*, is raised, the whole being substantially as shown in the accompanying photographic illustration.

I claim—

The design for a hook consisting of the frame *a* and vertical columns or posts *b*, having star ornamentations on their outer faces, as shown and described.

MELVILLE D. JONES.
